SMOKING PIPE

John C. Hogan, Charlotte, N. C.

Application February 6, 1936, Serial No. 62,682

2 Claims. (Cl. 131—12)

This invention relates to smoking pipes and the object of the invention is to provide a smoking pipe so equipped that the nicotine is precluded from mixing with the saliva and the moisture and saliva is prevented from entering the smoker's mouth. Briefly the invention consists in providing for the trapping of the saliva and for the passage of the smoke from the bowl of the pipe to the smoker's mouth in such a manner as to be free of all saliva and moisture thus tending to the greater enjoyment of pipe smoking.

The invention together with its objects and advantages will be best understood from a study of the following description taken in connection with the accompanying drawing wherein:

Figure 1 is a longitudinal sectional view through a pipe, on an enlarged scale and illustrating the application of the invention, and

Figure 2 is a sectional view taken substantially on the line 2—2 of Figure 1.

Referring to the drawing by reference numerals it will be seen that I have illustrated the invention as applied to a pipe consisting of a bowl 5 having an integral stem 6, the free end of which is equipped with a band 12 and abuts one end of a mouth piece 7. The bowl 5 is connected with the stem 6 through the medium of a passage 8 and the bore of the stem 6 is of a diameter materially greater than the diameter of a conventional pipe stem.

The mouth piece 7 is provided with a smoke passage 10 and at the end thereof where the mouth piece 7 abuts the stem 6 said mouth piece 7 is provided with a relatively large bore 11.

Accommodated within the bores of stem 6 and mouth piece 7, and overlapping the joint between the stem 6 and mouth piece 7 are a smoke tube 13 and a saliva tube or trap 14. The tubes 13 and 14 terminate short of the inner ends of the bores whereby to provide at the inner end of the bore of stem 6 a nicotine trap 9, and at the inner end of the bore 11 a chamber 16.

The tubes 13 and 14 are of such a shape in cross section, and as clearly shown in the drawing as to fit conformably within the bores of stem 6 and mouth piece 7, tube 14 being relatively large and having a curved wall as shown and a flat wall 14a which is the top wall of the tube.

Tube 13, is complementary to tube 14 and is substantially segmental in shape, having a curved peripheral wall and a bottom flat wall 13a which rests flatly on the wall 14a of the tube 14.

Each of the tubes is open at its respective opposite ends, and at the end thereof facing the chamber 9 tube 14 is provided with a knob equipped,

removable plug 15 that serves to close said end of the tube 14.

While I have illustrated tubes 13 and 14 as being constructed separately from one another it is understood that a single tube may be employed, and where a single tube is employed, the same will be cylindrical in cross section and will be provided with a suitable partition for dividing the single tube into a relatively large compartment having the same function as tube 14, and a relatively smaller compartment having the same function as tube 13.

In actual practice the smoke from the bowl 5 passes through the passage 8 into the nicotine trap 9. From the trap 9 the smoke passes through the tube 13 into the chamber 16, and from the chamber 16 through the smoke passage 10 of the stem to the smoker's mouth. Any saliva from the smoker's mouth will pass inwardly through the passage 10 into the chamber 16, and from the chamber 16 into the tube 14 where it is trapped, and not permitted to enter the nicotine trap 9 and consequently not permitted to mix with the smoke that passes through the trap 9 from the bowl 5 to the tube 13.

The chamber 16 is large enough so that any moisture that might form in the smoke tube 13 and be sucked into the chamber 16 by the smoke, will not jump the chamber 16 and pass into the smoke channel 10 but rather, such moisture will fall into the chamber 16 and carried by the saliva from the chamber 16 into the saliva trap tube 14.

Thus it will be seen that the smoke drawn into the smoker's mouth from the bowl 5 will be free of all moisture and saliva, thus insuring to the smoker a clean and more refreshing smoke than is obtained where the saliva and nicotine and other such moisture are permitted to mingle with the smoke as it passes from the channel 10 of the mouth piece 7 into the smoker's mouth.

When it is desired to clean the tubes 13 and 14, the mouth piece 7 may be readily separated from the stem 6, whereby access is then easily had to the tubes 13 and 14, and thus permitting these tubes to be readily removed and cleaned.

The parts may be reassembled, as is apparent, in a quick and efficient manner.

Having thus described the invention, what is claimed as new is:

1. A smoker's pipe including a bowl having a hollow stem with a restricted smoke passage and a mouth piece abutting at one end with one end of the stem, a chamber at the connected ends of the stem and mouth piece and a pair of segmental cylindrical tubes disposed alongside of one another.

other, said tubes collectively forming a completed cylinder and snugly fitted within the respective ends of the stem and mouthpiece, said tubes at one end terminating short of the bowl to provide
5 within the stem adjacent to the bowl a nicotine trap, and at the ends thereof remote from the bowl said tubes terminating short of the restricted smoke passage of the stem to provide a chamber connecting said tubes and the smoke passage,
10 and a plug removably disposed in the first named end of one of said tubes.

2. In a smoker's pipe, a bowl having a stem and

a mouth piece having one end abutting and connected with one end of the stem, a chamber at the connected ends of the stem and mouthpiece, a segmental cylindrical tube having its end portions snugly fitted respectively within the stem and the 5 mouthpiece, said end portions of the tube being spaced from the respective ends of the chamber, a plug removably fitted in the stem end of the tube to provide a saliva trap, and a smoke passage outwardly of the tube having communication 10 with the ends of the chamber.

JOHN C. HOGAN.
